WORK-POSITIONING MECHANISM.

1,401,248.

Specification of Letters Patent. Patented Dec. 27, 1921.

Application filed June 15, 1918. Serial No. 240,200.

To all whom it may concern:

Be it known that we, GEORGE GODDU and FRED L. MACKENZIE, citizens of the United States, residing at Winchester, in the county 5 of Middlesex, and Beverly, in the county of Essex, respectively, and State of Massachusetts, have invented certain Improvements in Work-Positioning Mechanisms, of which the following description, in connection 10 with the accompanying drawings, is a specification, like reference characters on the drawings indicating like parts in the several figures.

This invention relates to mechanism for 15 positioning work such, for example, as shoe stock for the performance of operations thereon, and the embodiment of the invention hereinafter specifically described will be set forth with particular reference to its 20 application to the insertion of fastenings in toplifts of heels.

In the manufacture of shoes of certain kinds, it is customary to affix a toplift to the heel of a shoe by metallic fastenings 25 inserted adjacent to each of the breast corners of the toplift and at the back of the toplift respectively. The head ends of the fastenings are visible on the tread surface of the heel of the finished shoe, for which 30 reason it is desirable to the end that the heel may present a symmetrical appearance that the fastenings be spaced equidistantly from the contour edge of the toplift, and that the fastenings inserted adjacent to the 35 breast corners of the toplift be disposed equidistantly from the breast edge of the toplift and be spaced from the breast edge of the toplift by a distance bearing a definite relation to the distance by which they 40 are spaced from the contour edge of the toplift, the distance by which the fastenings are spaced from the breast edge of the toplift being substantially equal to the distance by which they are spaced from the contour 45 edge of the toplift.

In order that fastenings may be inserted symmetrically in heels of different sizes and to attain uniformity of appearance of shoes having heels of varying sizes, 50 it is further desirable that the spacing of the fastenings from the edges of the heel be proportioned to the sizes of the heels so the fastenings will be spaced farther from the breast edge and contour edge of 55 a large heel than from the corresponding

edges of a small heel. Accordingly, an important feature of the invention resides in the provision of means for positioning the breast corners of a heel successively at substantially equal distances from the point 60 of operation on the heel and adjustable for different sizes of heels so that the point of operation on a large heel may be disposed farther from the breast edge of the heel than from the corresponding edge of a 65 smaller heel. Preferably, and, in the illustrated construction, the positioning means comprises a plurality of gage members so connected that an adjustment of one of said members effects a corresponding adjustment 70 of the other.

In accordance with a still further feature of the invention, one of a plurality of gage members is mounted for movement by the work relatively to the other gage member 75 to facilitate the operation on a heel of a machine employing an awl feed by which the work is moved from the position in which it is first presented to the machine prior to the completion of the operation of 80 the machine thereon. Preferably and as shown the movable gage member is normally urged yieldingly toward the other gage member and is so constructed as to cause its gaging surface to move substantially in the direction of the movement of the work.

In the illustrated embodiment of the invention, the positioning means for the toplift comprises gage members formed to present shouldered gaging surfaces for engagement respectively with the breast corners of a toplift and with other gaging surfaces arranged for engagement with the contour edge of the toplift, the contour edge gaging 95 surface of each of said members being arranged to engage the contour edge of a heel when a breast corner of the heel is presented against the shouldered gaging surface of the other gage member.

Although the invention will be herein-after described as applied to a machine for inserting fastenings at three points, for example, for attaching a toplift to a heel, it is recognized that the invention is not restricted in its application to such specific use, and it is further recognized that the gage members and the means for mounting and adjusting them may be modified without departing from the principles of the in- 110

vention. It is, therefore, intended that the scope of the invention shall be limited only as required by the language of the appended claims.

5 In the drawings:

Figure 1 is a broken view of the head of a fastening inserting machine having my invention applied thereto;

Fig. 2 is a plan view taken substantially 10 along the line 2—2 of Fig. 1;

Fig. 3 is a front view showing the invention applied to the head of a fastening inserting machine;

Fig. 4 is a view in cross section along the 15 line 4—4 of Fig. 2 looking in the direction of the arrow;

Fig. 5 is a view showing the relative arrangement of the toplift and the gage members for the insertion of a fastening adjacent to one of the breast corners of the toplift;

Fig. 6 is a view showing the relative arrangement of the toplift and the gage members for the insertion of a fastening adjacent 20 to the other of the breast corners of the toplift, and

Fig. 7 is a view showing the relative arrangement of the toplift and the gage members for the insertion of a fastening adjacent 25 to the back of the toplift.

The work positioning mechanism is herein illustrated as applied to a fastening inserting machine of the type employed for inserting headless fastenings formed from 30 wire, such fastenings being generally denominated "slugs" and a machine for inserting such fastenings being disclosed in the patent to Casgrain No. 786,190, granted March 28, 1905. As illustrated, the frame 6 35 of the work positioning mechanism is pivoted to the head 2 of the fastening inserting machine at 4, and slidably mounted in a boss formed on the head 2 of the machine is a spring pressed plunger 8 coöperating 40 with the inclined surface 10 formed on one of the bosses 12 of the frame 6. The plunger 8 operates normally to retain the work positioning mechanism in its operative horizontal position but yields to permit the 45 frame 6 and the parts carried thereby to be turned downwardly on the pivot 4.

Mounted on the frame 6 are gage members 50 14 and 16 formed to present shouldered gaging surfaces 18 and 20 for engagement with the breast corners of a toplift and preferably curved gaging surfaces 21 and 22 for engagement with the contour edge of the toplift. The fastenings are impelled into the toplift by a driver 23, openings being 55 made in the toplift through the instrumentality of an awl 24 to receive the fastenings inserted by the driver. The gaging surfaces 18 and 20 are so arranged relatively to the awl as to position the toplift in such manner 60 that the awl when projected downwardly 65

penetrates the toplift at the point where the fastening should be inserted.

It is desirable, in order to make the different pieces of work uniform and symmetrical in appearance, that the fastenings 70 be inserted at a greater distance from both the contour edge and the breast edge of the toplift in operating on a relatively large toplift than when operating on a smaller toplift. Means are provided for adjusting 75 the gaging surfaces 18 and 20 to adapt the work positioning mechanism for use in operating on toplifts of varying sizes, and we have so constructed the adjusting means for the gage members 14 and 16 that an adjustment of one of said gage members to adapt 80 it for use in operating on a toplift of a certain size will effect a corresponding adjustment of the other gage member to adapt it for use in operating on a toplift of like 85 size. To this end, the gage member 14 is fulcrumed at 26 on the carrier or plate 28 90 slidably mounted in the frame 6, and the gage member 16 is connected to the gage member 14 by a pin and slot connection comprising the pin 30 and the slot 31 whereby movement of the gage member 14 is transmitted to the gage member 16. The gage member 14 is adjusted about the fulcrum 26 by means of a handle 32 and is maintained in any position of adjustment to which it may be moved by a bolt or the like 95 34 which passes through a slot in the plate 28. The pin 30 and slot 31 form a connection between the gage members 14 and 16 100 whereby adjustment of the gage member 14 effects an equivalent adjustment of the gage member 16 and also permit movement of the gage member 16 independently of the gage member 14 for a purpose to be herein- 105 after set forth.

Fig. 5 shows in full lines the position in which a heel B comprising a toplift A is presented to the machine. As shown, the breast corner of the heel B is engaged with the shouldered gaging surface 20 of the gage member 16. From an inspection of Fig. 5, it will be apparent that if the gaging surfaces 18 and 20 are moved toward each other, the fastening will be inserted in 110 closer proximity to the breast edge of the heel than before, whereas, if the gage members 14 and 16 are adjusted away from each other, the fastening will be inserted at a 115 point more remote from the breast edge of the heel than before.

In order to determine properly the distance by which the fastening is spaced from the contour edge of the heel, means is provided for adjusting the gage members 14 and 16 together toward or from the plane 120 of operation of the fastening inserting mechanism. As shown, such means comprises a stud shaft 36 journaled in bearings 125 in the frame 6 and toothed or corrugated 130

- at 38 for engagement with teeth or corrugations formed at 40 on the slide or carrier 28. For convenience of manipulation, the stud shaft 36 is provided with a handle 42. A spring 44 at the end of the shaft 36 opposite the handle 42 is interposed between set nuts 46 and the frame 6 and exerts friction whereby the gage carrier 28 is maintained in any position of adjustment 5 to which it may be moved. From the foregoing it will be plain that, if a heel of greater size than the preceding heel is to be operated upon, the handle 32 will be manipulated to move the gage members 14 and 16 away from each other which will cause the fastening to be inserted at a greater distance from the breast edge of the heel. The handle 42 will also be manipulated to move gage members 14 and 16 rearwardly away from the plane of operation 10 of the fastening inserting mechanism which will increase the distance by which the fastening will be spaced from the contour edge of the heel.
- 25 In the operation of the fastening inserting machine, the awl is moved laterally subsequently to its projection into the work to bring the opening thus made in the work into alignment with the driver 23. Each 30 of the shouldered gaging surfaces 18 and 20 has a portion arranged transversely of the direction of movement of the work and intersecting with the contour edge gaging surface 21 or 22, the angle thus formed 35 engaging the breast edge of the heel when the heel is presented to the fastening inserting machine as indicated in Figs. 5 or 6. In order to permit movement of the work by the awl, we have so mounted the gage 40 member 16, which is carried by that side of the carrier 28 toward which the work is moved by the awl, as to permit said gage member 16 to be moved by the work independently of the gage member 14. To this 45 end, the gage member 16 is fulcrumed at 48 on the link 50 which is in turn fulcrumed at 52 to the gage slide or carrier 28. The link 50 and the gage member 16 carried thereby are normally urged toward the gage 50 member 14 by a spring 54 which yields to permit movement of the gage member 16 when the work is fed by the awl. Movement of the gage member 16 toward the gage member 14 is limited by stop 55, Fig. 2.
- 55 The awl moves in a substantially straight line and in order that the work may be effectively guided and supported while it is being fed by the awl, we so control the movement of the gage member 16 as to cause 60 the gaging surface 20 thereof to be moved substantially in a straight line and parallel to the path of movement of the awl. Thus the inclination of slot 31 in arm 56 of the gage member 16 is such as to prevent substantial inward or outward movement of 65
- the gaging surface 20 as link 50 is swung about its pivot 52. The pin 30 acting against the end of the slot 31 in the arm 56 of the gage member 16 limits the movement of the gage member 16 under the impulse of the spring 54 and thus determines the normal positions of the gaging surfaces 20 and 22.
- 70 A horn 58 may be provided for supporting the heel against the force exerted thereon by the fastening inserting mechanism.
- The operation of the device will be apparent from an inspection of Figs. 5, 6 and 7 of the drawings. The heel may be first presented to the fastening inserting mechanism in the position shown in full lines in Fig. 5, following which the awl penetrates the heel at the point indicated by the upper small circle defined by a full line and moves it and the gage member 16 to the positions 80 shown in broken lines in said figure, the point of fastening insertion being indicated by the lower circle defined by a broken line. Analogously, the full lines in Fig. 6 indicate the position in which the heel is presented to the fastening inserting mechanism for the insertion of a fastening adjacent to the other breast corner of the heel, and the broken lines indicate the positions to which the parts are moved by the awl, the lower 90 circle indicating the point of fastening insertion. In Fig. 7 is indicated in full lines the position in which the heel is first presented to the fastening inserting mechanism for the insertion of a fastening adjacent to the back of the heel, the parts being moved from full line position to broken line position by the awl following penetration of the work by the awl. In each case, the gage member 16 is moved backwardly in opposition to the action of the spring 54 to permit movement of the work from the position indicated in full lines to the position indicated in broken lines. It will be understood that the order in which the 100 several fastenings are inserted may be varied at the will or convenience of the operator.
- Having described the invention, what we claim as new and desire to secure by Letters Patent of the United States is:
1. In a machine of the class described, means for operating on a heel and normally stationary means adjustable to accommodate heels of different sizes for positioning the breast corners of the heel in different operative positions of the heel at substantially equal distances from the point of operation of the operating means on the heel.
- 115 2. In a machine of the class described, means for operating on a heel, and normally stationary means for positioning the heel relatively to the operating means comprising a plurality of gaging surfaces one constructed to engage one of the breast corners of the heel in one operative position of the 120
- 125
- 130

heel and the other to engage the other breast corner of the heel in another operative position of the heel and means for adjusting said gaging surfaces in opposite directions from the point of operation of the operating means on the heel to adapt the positioning means to locate heels of different sizes.

3. In a machine of the class described, the combination with means for operating on a heel, of a gage member providing a shouldered gaging surface adapted for engagement with a breast corner of the heel to position the heel relatively to the operating means, means formed to present a gaging surface for engagement with the contour edge of the heel on the same side of the heel as said breast corner upon engagement of the breast corner with said shouldered gaging surface, and means for adjusting said shouldered gaging surface and said contour edge gaging surface relatively to each other.

4. In a machine of the class described, the combination with means for operating on a heel, of a member formed to present a shouldered gaging surface adapted for engagement with one of the breast corners of the heel to determine one operative position of the heel relatively to the operating means, and a member spaced from the first-mentioned member by a distance less than the width of the heel and formed to present a shouldered gaging surface for engagement with the other breast corner of the heel to determine a second operative position of the heel relatively to the operating means, and means for adjusting said members relatively to each other.

5. In a machine of the class described, the combination with means for operating on a heel, of a carrier, a gage member mounted upon the carrier and formed to present a shouldered gaging surface for positioning a heel relatively to the operating means by engagement with a breast corner of the heel, a second gage member formed to present a gaging surface for engagement with the contour edge of the heel adjacent to said breast corner, means for adjusting said gaging surfaces toward and from each other, and means for adjusting the carrier toward and from the operating means to accommodate heels of varying sizes.

6. In a machine of the class described, the combination with means for operating on a heel, members formed to present gaging surfaces for selective engagement with the breast corners of the heel to locate the heel in different positions for operation by said means, and common adjusting means for said members so constructed and arranged that when one of said members is adjusted to adapt it to a heel of a certain size the other is adjusted for a heel of like size, said means comprising means for adjusting said members together in the same direction and

other means for adjusting said members in opposite directions.

7. In a machine of the class described, the combination with means for operating on a heel, of spaced members formed to present shouldered gaging surfaces for selective engagement with the breast corners of the heel to locate the heel in different operative positions relatively to the operating means, each of said members being formed to present a gaging surface for engagement with the contour edge of the heel upon engagement of a breast corner of the heel with the shouldered gaging surface of the other of said members, and means for adjusting said members toward and from each other.

8. In a machine of the class described, the combination with means for operating on a heel, of spaced members each formed to present a shouldered gaging surface for positioning the heel relatively to the operating means, and means for adjusting said members comprising connections between said members for effecting an equivalent adjustment of one of said members upon adjustment of the other of said members, said connections being constructed and arranged to permit movement of one of said members independently of the other.

9. In a machine of the class described, the combination with means for operating on a heel constructed and arranged to move the heel, a member formed to present a gaging surface arranged transversely of the direction of movement of the heel for engagement with the breast edge of the heel to position the heel relatively to the operating means, a member providing a gaging surface spaced from the first-mentioned gaging surface and constructed and arranged for engagement with the contour edge of the heel, means for mounting the first-mentioned gaging surface for movement relatively to the second-mentioned gaging surface, and means for maintaining the first-mentioned gaging member against the breast edge of the heel, said means being constructed and arranged to yield thereby to permit movement of the first-mentioned gaging surface relatively to the second-mentioned gaging surface in the direction of the movement of the heel.

10. In a machine of the class described, the combination with means for operating on a heel as it is moved past said operating means, of relatively movable gaging members each formed to present a shouldered gaging surface one portion of which is arranged transversely of the direction of movement of the heel, said members being spaced from each other so that one of said gaging surfaces is adapted for engagement with one of the breast corners of the heel and the other of said gaging surfaces is adapted for engagement with the other breast corner of the heel for positioning the heel relatively to the

- operating means, and means for urging one of said gaging surfaces in a direction opposite to the direction of the movement of the heel, said means being constructed and arranged to yield thereby to permit said gaging surface to move relatively to the other gaging surface in the direction of the movement of the heel.
11. In a device of the class described, mechanism constructed and arranged to provide shouldered gaging surfaces for engagement with the breast corners of a heel and other surfaces disposed adjacent to each other and coöperating to position the heel independently of the shouldered gaging surfaces by engagement with the contour edge of the heel, and means for adjusting said gaging surfaces relatively to each other to adapt them for different sizes of heels.
12. In a device of the class described, mechanism constructed and arranged to provide relatively movable gaging surfaces spaced from each other and faced substantially in the same direction so as to position a heel by engagement with the contour edge of the heel, and means for normally urging one of said gaging surfaces toward the other constructed to yield thereby to permit movement of the heel.
13. In a machine of the class described, the combination with means for operating on a piece of work as it is moved past said operating means, a member formed to present a gaging surface arranged transversely of the direction of movement of the work past the operating means for engagement with an angular portion of the work to position the work relatively to the operating means, a member movable relatively to the first-mentioned member and formed to present a gaging surface for engagement with the contour edge of the work upon the presentation of the work to said first-mentioned gaging surface, and means for normally urging said last-mentioned member toward said first mentioned member constructed to yield in the direction of movement of the work.
14. In a device of the class described, a carrier, a member normally fixed to the carrier and formed to present a gaging surface, a second member movably mounted upon the carrier and formed to present a gaging surface, means for normally urging said second member toward said first member and connections between said members for effecting adjustment of one of said members in one direction upon adjustment of the other of said members in the opposite direction.
15. In a device of the class described, a carrier, a gage member mounted on the carrier and formed to present a shouldered gaging surface for engagement with the breast corner of a heel, a second gage mem-
- ber mounted on the carrier and formed to present a gaging surface for engagement with the contour edge of the heel on the same side of the heel as said breast corner, and means for adjusting said members relatively to each other to accommodate heels of varying sizes.
16. In a device of the class described, a carrier, a gage member pivoted on the carrier, a link pivoted on the carrier, a second gage member fulcrumed on said link, and connections between said gage members for effecting adjustment of one of said gage members upon adjustment of the other of said gage members.
17. In a device of the class described, a carrier, a gage member pivoted on the carrier, a link pivoted on the carrier, a second gage member fulcrumed on said link, arms extending from said gage members toward each other, and a pin and slot connection between said arms for effecting a substantially equivalent adjustment of one of said gage members about its pivot upon adjustment of the other of said gage members, and means for pivotally adjusting said gage members.
18. In a machine of the class described, means for operating on a piece of work as it is moved past said operating means, a gage member formed to present a gaging surface arranged transversely of the direction of movement of the work, said gage member being mounted to permit movement of the gaging surface, and means for controlling the movement of the gaging surface constructed and arranged to cause the gaging surface to move substantially in the direction of movement of the work.
19. In a device of the class described, a carrier, a gage member pivotally connected to the carrier for movement relatively thereto and comprising two arms arranged substantially at right angles to each other, one of said arms being formed to present a shouldered gaging surface faced outwardly from the body of said member for engagement with the breast corner of a heel, and means operating on the other of said arms to control the direction of movement of said gaging surface.
20. In a device of the class described, a normally stationary carrier, a gage member pivotally mounted on the carrier and formed to present a gaging surface, means for determining the normal position of the gaging surface, controlling means for the gage member operative to cause the gaging surface to move substantially in a straight line, and a second gage member formed to present a gaging surface in spaced relation to said first-mentioned gaging surface.
21. In a device of the class described, a carrier, a gage member pivoted on said carrier, a second gage member pivoted on said

- carrier, means normally urging said gage members toward each other, and a pin and slot connection between said gage members for effecting an equivalent adjustment of 5 one of said gage members upon adjustment of the other of said gage members, said pin and slot connection being constructed and arranged to permit bodily movement of one of said gage members relatively to the other 10 gage member and to cause the gaging surface of said movable gage member to be moved substantially in a straight line.
22. In a machine of the class described, means for operating on a heel, gage members formed to present spaced shouldered gaging surfaces faced outwardly from the bodies of said members and arranged at such a distance from one another as to position a heel relatively to the operating 15 means by engagement with a breast corner of the heel and with a portion of the contour edge of the heel adjacent to that breast corner respectively, and means for adjusting said gage members in opposite directions 20 from the point of operation of the operating means on the heel to adapt them to locate heels of different sizes in proper relation to the operating means.
23. In a machine of the class described, 30 a carrier, heel locating members pivoted on the carrier, and connections between said members for effecting corresponding opposite adjustment of one of said members upon adjustment of the other of said members, 35 and arranged to permit yielding movement of one of said members from adjusted position and away from said other member.
24. In a machine of the class described, means for operating on a heel, means for 40 positioning the breast corners of a heel successively at substantially equal distances from the point of operation on the heel, and means for adjusting the positioning means to adapt it for heels of different sizes so 45 that the point of operation on a larger heel may be disposed farther from the breast edge of the heel than from the corresponding edge of a smaller heel.
25. In a machine of the class described, 50 means for operating on a heel, means constructed and arranged without adjustment to position the breast corners of a heel and the back of the heel successively at substantially equal distance from the point of operation on the heel, and means for adjusting the positioning means to accommodate it to heels of varying sizes.
26. In a machine of the class described, 55 means for operating on a heel, and a pair of gage members fixedly maintained against movement normal to the contour edge of the heel and alternatively operable to engage the contour edge of the heel and arranged for positioning the heel so that the 60 operation may be performed adjacent to either side of the heel according to whether one or the other of the gage members is utilized to engage the contour edge of the heel.
27. In a machine of the class described, 70 means for inserting a metallic fastening in a shoe, and a pair of gage members located upon opposite sides of the fastening inserting means fixedly maintained against movement normal to the contour edge of the work 75 and alternatively operable to engage the contour edge of the work and so arranged that the fastenings will be inserted adjacent to either side of the shoe according as said contour edge is brought into engagement 80 with one or the other of the gage members.
28. In a machine of the class described, means for operating on a heel, and a pair of gage members fixedly maintained against movement normal to the contour edge of 85 the heel and having capability of independent relative movement, said gage members being alternatively operable to engage the contour edge of the heel and so arranged that when one of said members is utilized 90 to position the contour edge of the heel the other of said members may move from its normal position to permit the performance of the operation upon the heel.
29. In a machine of the class described, 95 means for operating on a heel, a pair of gage members on opposite sides of the operating means fixedly maintained against movement normal to the contour edge of the heel, and alternatively operable to engage the contour edge of the heel, and so arranged that the operation may be performed adjacent to either side of the heel according as the contour edge is brought 100 into engagement with one gage member or the other, and means for adjusting said gage members relatively to each other and to the operating means.
30. In a machine of the class described, 105 means for inserting a metallic fastening in a shoe, a pair of gage members on opposite sides of said fastener inserting means and alternatively operable to engage the contour edge of the work, and means for adjusting said gage members relatively toward and from each other and the operating means to adjust the distance of the fastenings from the contour edge of the work 110 in which they are inserted.
31. A work positioning device comprising 115 a pair of gage members fixedly maintained against movement normal to the contour of the work and supported so that one may move relatively to the other in a direction perpendicular to said normal in response to pressure by the work.
- In testimony whereof we have signed our names to this specification.
- GEORGE GODDU.
- FRED L. MACKENZIE.

Certificate of Correction.

It is hereby certified that in Letters Patent No. 1,401,248, granted December 27, 1921, upon the application of George Goddu, of Winchester, and Fred L. Mackenzie, of Beverly, Massachusetts, for an improvement in "Work-Positioning Mechanisms," an error appears in the printed specification requiring correction as follows: Page 1, line 84, for the word "constructed" read *controlled*; and that the said Letters Patent should be read with this correction therein that the same may conform to the record of the case in the Patent Office.

Signed and sealed this 11th day of July, A. D., 1922.

[SEAL.]

KARL FENNING,

Acting Commissioner of Patents.
